UNITED STATES PATENT OFFICE.

EDWARD J. KEARNEY, OF WAUWATOSA, AND THEODORE TRECKER, OF WEST ALLIS,
WISCONSIN.

MILLING-MACHINE.

1,053,296.

Specification of Letters Patent. Patented Feb. 18, 1913.

Application filed May 29, 1912. Serial No. 700,379.

To all whom it may concern:

Be it known that we, EDWARD J. KEARNEY and THEODORE TRECKER, citizens of the United States, residing at Wauwatosa and West Allis, respectively, county of Milwaukee, and State of Wisconsin, have invented new and useful Improvements in Milling-Machines, of which the following is a specification.

10 Our invention relates to improvements in milling machines.

The object of our invention is to provide a rigid over-arm structure for milling machines, whereby the out bearing hanger arm 15 may be securely held in the exact position required for supporting the arbor.

In carrying out the above object, we employ a set of parallel over-arms, with both of which the out bearing hanger is adjustably engaged, and we also provide means whereby either one of the over-arms may be removed, either wholly or partially, independently of the other, to allow the out bearing hanger to be swung to a position of 25 non-use in substantially the same manner as in the milling machines heretofore constructed with a single over-arm.

In the drawings—Figure 1 is a front elevation of a portion of a milling machine embodying our invention. Fig. 2 is a side elevation of the same.

Like parts are identified by the same reference characters in both views.

1 is a milling machine column provided with a cap member 2, preferably integral with the column and provided with parallel apertures to receive a plurality of over-arms 3 and 4, which are mounted to slide through the column apertures, in which the over-arms closely fit. They can be rigidly secured in position by slotting the cap member in a horizontal plane and employing clamping bolts 6 to force the upper part of the cap downwardly, the slots 7 permitting such 45 downward movement and the material of which the cap is composed yielding sufficiently to allow the parts to bind upon the over-arms.

10 is a hanger or out bearing member, 50 adapted to support the arbor out-bearing member 11 from the over-arms 3 and 4, which over-arms pass through suitable openings in the upper portion of the hanger.

This hanger is provided with slots 12 extending vertically from its over-arm apertures to its upper margin, whereby the hanger may be clamped upon the over-arms by a cross bolt 13 and nuts 14.

When the hanger is in position of use, as shown by full lines in Fig. 1, it is rigidly supported by both of the over-arms 3 and 4, and it is therefore impossible for its lower end to be out of line with the axis of the arbor actuating spindle. It is also impossible for the hanger arm to swing from side to side and cramp the arbor. If it is desired to swing the out bearing hanger arm to a position of non use, as indicated by dotted lines in Fig. 2, it is merely necessary to loosen the clamping bolt 13 and push one 70 of the over-arms 3 or 4 inwardly through the column cap 2, whereupon the hanger arm may be swung upon the other over-arm to any desired position, and if necessary, locked in such position by the nuts 14 and 75 bolt 13. When the out bearing hanger 10 is in position of use, it will not be necessary to clamp the same in position on the over-arms 3 and 4, except to prevent longitudinal movements, all lateral or swinging movements being prevented by employing a plurality of over-arms.

We claim—

1. The combination with a milling machine column, of a plurality of over-arms 85 adjustably mounted in said column, and an out bearing hanger adapted to support a cutter arbor and detachably engaging each of said over-arms.

2. The combination with a milling machine column, of a plurality of over-arms 90 adjustably mounted in said column, and an out bearing hanger adapted to support a cutter arbor and detachably engaging each of said over-arms, said over-arms being each 95 adjustable independently of the other into and out of supporting relation to the out bearing hanger.

In testimony whereof we affix our signatures in the presence of two witnesses.

EDWARD J. KEARNEY.
THEODORE TRECKER.
